UNITED STATES PATENT OFFICE.

JEROME R. MARCUS, OF CHICAGO, ILLINOIS.

HYDRAULIC-JACK-OPERATING PUMP.

Application filed November 8, 1928. Serial No. 146,925.

My invention relates to hydraulic jacks and more particularly to apparatus of the above character adapted for portable use, such as for lifting automobiles and other loads, an object being to provide a jack of this character adapted for use in lifting the load without requiring the operator to get under the car or load to place or operate the jack, thereby permitting the operator to work 10 in a comfortable position and also eliminating the danger of soiling or tearing his clothes.

There are various features to my invention and they will be more particularly pointed out in the ensuing part of the specification and appended claims.

For a better understanding of my invention reference is to be had to the accompanying drawings, in which—

20 Fig. 1 is a vertical transverse section through the pump unit;

Fig. 2 is a vertical cross section through a suitable jack adapted for use with the pump, both being adapted for mounting upon a 25 single base so as to form a unit structure;

Fig. 3 is a view of the reversing valve in a position for releasing the fluid to lower the jack, the valve in Fig. 1 being shown in a 30 position for pumping the fluid into the jack to raise the same;

Fig. 4 is a transverse sectional view along the line 4—4 of Fig. 1;

Fig. 5 is a vertical cross sectional view along the line 5—5 of Fig. 1; and

35 Fig. 6 is a sectional view showing one of the valves more in detail.

Referring now more in detail to the apparatus as illustrated, I provide a suitable reservoir R which contains the fluid preferably 40 used for operating the jack, and for this purpose oil may be provided which is placed in the reservoir through the cap 10. This reservoir preferably surrounds the pump P, the reservoir comprising an outer circular casing 45 11 having a cap 12 applied thereto with the casing 11 fixed into the base B. The pump P may be of any suitable construction and I have shown a cylinder portion 13 having a piston 14 operating therein and which may 50 be operated in any suitable manner. I have here shown a hand operated pump with the piston rod 15 supporting a handle 16.

To control the flow of fluid between the pump and jack I provide a valve V which is 55 in the nature of a two way four port valve with the ports suitably connected to the res-

ervoir and pump so that the fluid may be properly controlled so that it may be drawn from the reservoir and pump into the jack with the valve shown in the position of Fig. 60 1 or with the valve shown in the position of Fig. 3 the fluid may be forced back from the jack through the pump so as to be returned to the reservoir and permit release of the 65 jack.

The said valve may be constructed in any suitable manner and I have shown it mounted in the base B and comprising a rotatable gate or plug 17 having passages 18 and 19 terminating in ports adapted to register with 70 the ports leading to passages connected to other parts of the apparatus.

The fluid from the reservoir is adapted to pass down through a passage 20 leading to port 21 of the valve. Passage 19 of the valve 75 then leads to port 22 which is connected by the passage 23 to an intermediate chamber 24 having a spring pressed pump inlet valve 25 connected therewith and so positioned that the oil is drawn upwardly through this valve 80 by the upward stroke of the pump piston. Thus with each upward stroke of the piston oil is drawn from the reservoir over the stated path and into the cylinder of the pump. On the down stroke of the piston the oil is forced 85 through the pump outlet valve 26 in the direction of the arrows indicated on the left hand side, the oil then being forced through passage 27 and valve passage 18 to the outlet 28. This outlet is connected by a suitable 90 conduit 29 to the jack J, which latter is preferably in the form of a piston jack adapted to be raised when the fluid is pumped into its cylinder. This jack may be controlled by a valve 30, thus permitting the jack to be held 95 in a raised position by a valve close to its cylinder.

Referring again to the reversing valve V, the gate member 17 thereof is rotatably supported in the base as shown also in Fig. 4, 100 being held in position in a suitable manner and preferably by a cap 31 through which the valve stem 32 extends. A suitable operating handle 33 is provided, this being removably secured to the end of the stem 32 and set with- 105 in a recess of the casing so as to prevent its exposure to accidental operation.

The jack and pump units may be mounted upon a single base 34 so that the apparatus as a whole may be used as a portable unit 110 movable from place to place.

In the operation of the apparatus as al-

ready referred to we have described how the fluid is drawn from the reservoir to the pump and then forced through the valve as shown in Fig. 1 out to the jack J to lift the load.

Assuming now that the jack and load are to be lowered, the operator may reverse or move the valve V to its alternate position as indicated in Fig. 3, thereby altering the connections so that the fluid in the pump may be forced back into the reservoir. This return of the fluid and lowering of the jack may be accomplished either by the load itself or through the action of the pump. For instance, with a heavy load on the jack and the oil in a very fluid state, the reversal of the valve as stated would permit the oil to be forced back into the reservoir by the load on the jack. In such case the oil would flow over a path from the jack cylinder through passage 28 of the base, valve passage 19 and passage 23 to the chamber 24, then passing upwardly through valve 25 then through valve 26, passage 27, valve passage 18, port 21 and passage 21 to the reservoir R. Thus the mere reversal of the valve V would permit a restoration of the jack without any other operation.

Assuming, however, that the load is not sufficient to force the oil back into the reservoir, or that the oil has become hardened by the cold or for other reasons, the reversal of the valve into its position of Fig. 3 and the operation of the pump P would cause the pump to draw the oil back into the reservoir and lower the jack. This operation is brought about in that upon each upward stroke of the piston of the pump P there is a suction which will draw the fluid from the jack through the lower passage of the valve into the chamber 24 and then up through valve 25 into the pump cylinder. Upon the down stroke of the pump piston this fluid which was drawn in on the last stroke is now forced through the outlet valve 26 but cannot return through inlet valve 25. From outlet valve 26 the fluid continues through passage 27 and valve passage 28 to conduit 21 and up into the reservoir R.

It will thus be seen that by the simple manipulation of the valve V the apparatus may be operated to lift the jack and then by the simple reversal of the controlling valve V the jack may be lowered to force the oil back into the reservoir, or it may be drawn back into the reservoir by the force of the pump P if necessary.

What I claim as new and desire to secure by United States Letters Patent is:—

1. A hydraulic jack including a fluid reservoir, a pump including spring pressed inlet and outlet valves for the pump cylinder, a piston, a manually operated reversing valve, a jack, and conduits connecting the jack, reversing valve, reservoir and pump valves, and means in said reversing valve for controlling

said connections to cause the pump to draw the fluid from the reservoir and force it into the jack to operate the latter or to cause the pump to draw the fluid from the jack and force it back into the reservoir.

2. A hydraulic jack including a fluid reservoir, a pump including spring pressed inlet and outlet valves for the pump cylinder, a piston, a manually operated reversing valve, a jack, and conduits connecting the jack, reversing valve, reservoir and pump valves, and means in said reversing valve for controlling said connections to cause the pump to draw the fluid from the reservoir and force it into the jack to operate the latter or to cause the pump to draw the fluid from the jack and force it back into the reservoir without varying the pump valves.

3. A hydraulic jack including a fluid reservoir; a pump including a cylinder, a piston, an automatic inlet valve and an automatic outlet valve; a jack, a manually operated two way controlling valve, and conduits connecting the valves, jack and reservoir for causing the pump to draw fluid from the reservoir and force it into the jack to operate the latter with the manual valve in one position or cause the pump to draw the fluid from the jack and force it back into the reservoir with the manual valve in its other position.

4. A hydraulic jack including a fluid reservoir, a pump including a cylinder, a piston, an inlet valve and an outlet valve; a jack, a two way valve having a gate and two pairs of connecting ports forming four ports in all, connections from the reservoir, the two pump valves, and the jack to said ports, said valve ports and gate being arranged to connect the pump inlet valve and reservoir, and the pump outlet valve and a jack connected port to operate the jack by the pump, or to connect the pump inlet valve and jack connected port and the pump outlet valve and reservoir to release the jack.

5. A hydraulic jack including a fluid reservoir, a pump including a cylinder, a piston, an inlet valve and an outlet valve; a jack, a two way valve having a gate and two pairs of connecting ports, connections from the reservoir, the two pump valves, and the jack to said ports, said valve ports and gate being arranged to connect the pump inlet valve and reservoir, and the pump outlet valve and a jack connected port to operate the jack by the pump, or to connect the pump inlet valve and jack connected port and the pump outlet valve and reservoir to release the jack during a continued like operation of the pump piston and pump valves.

6. A hydraulic jack including a cylinder and piston jack, a unit pump structure having a cylinder, a piston and inlet and outlet valves, a fluid reservoir surrounding the pump cylinder, a common base for the pump cylinder and reservoir, a two way four port

valve in said base, one of said ports being for connection with the jack cylinder; and conduits in said base connecting the reservoir, the pump valves and the remaining three 5 ports of the two way valve, said connections and two way valve being arranged to cause the pump to draw the fluid from the reservoir and force it through the jack port into the jack cylinder or draw the fluid from the 10 jack cylinder and force it back into the reservoir according to the position of the two way valve.

7. A hydraulic jack including a cylinder and piston jack, a pump having a cylinder, 15 piston, and inlet and outlet valves, a fluid

reservoir, a valve in the form of a solid cylinder having two unconnected transverse passageways therethrough terminating in four parts on the outer surface thereof, conduits leading from the jack cylinder, the two 20 valves, and fluid reservoir and terminating at said valve in positions adapting them to be registered with the ports in said valve and means for turning the valve to line the parts up to pump fluid from the jack cylinder into 25 the reservoir, or from the reservoir into the jack cylinder.

In witness whereof, I hereunto subscribe my name this 1st day of November, 1926.

JEROME R. MARCUS.
